[57] CLAIM

The ornamental design for a motor home, as shown and described.

DESCRIPTION

FIG. 1 is a front side perspective view of the motor home showing the new design;

FIG. 2 is an enlarged front elevational view thereof;

FIG. 3 is an enlarged rear elevational view thereof;

FIG. 4 is a top plan view thereof;

FIG. 5 is a left side elevational view thereof; and,

FIG. 6 is a right side elevational view thereof.

The broken line showing of the windows and doors on the right and left side of the motor home in FIGS. 1, 5 and 6 of the drawing is for illustrative purposes only and forms no part of the claimed design.

FIG. 1

FIG. 3
